United States Patent Office.

WILLIAM MORGEY, OF WILMINGTON, DELAWARE.

Letters Patent No. 79,677, dated July 7, 1868.

IMPROVEMENT IN BENDING FIFTH-WHEELS.

The Schedule referred to in these Letters Patent and making part of the same.

Be it known that I, WILLIAM MORGEY, of the city of Wilmington, in the State of Delaware, have invented a new and useful Machine for Bending Fifth-Wheels and clip-circles of carriages, and sizing and lining-clips; and I do hereby declare that the following is a full, clear, and exact description of the construction and operation of the same, reference being had to the annexed drawings, making a part of this specification, in which—

Figure 1 is a side view, and

Figure 2 a plane view of the machine.

A is the table or stand; b is the levelling-plate; D, turn-table; E is the plate for forming circles, and is fastened to the turn-table by screw-bolts; m is a moon-shaped lever; F, sizing and lining lever, in connection with which I use an additional lever at g, for holding down clip-circle while levelling it; h is an eccentric-lever, with rollers i and j attached, the roller j always being detached while bending the clip-circle; k is a slotted slide, provided for extending eccentric-lever h to suit size of turn-tables.

I construct my bending-machine of iron, except the framework, which is of wood, as is also a portion of the surface of the table, fitting close to the cast-iron plate b used for levelling.

When the clip is heated, I place it on the turn-table d, against the plate e, force down the lever f in the clip, draw up the moon-shaped lever m, and force the circle against the plate e, slip a binding-ring at s on the levers f and m, which then form a firm handle. I then hammer the clip up to lever F, which forms the exact size of and brings the clip on a line with the axle of the carriage for which it is made. I then draw up the eccentric-roller f, bearing on the turn-table d, with roller j raised or detached, and having set a lever in place at g, draw around my turn-table, which forms a perfect circle of the clip-wheel, until I come to lever at g; then draw down lever into the clip at g, throw the eccentric-lever out of the way, which gives me a clear table. I then press down with the lever at g, and hammer out the twist in clip-circle.

In bending full circles, I remove the moon from the moon-lever, use a lever of the same shape without a moon, catch the plain iron between the two levers, take off lever at g, move round the eccentric-lever h with roller j brought down by means of lever o, slip a bending-ring on turn-table levers, and by making one revolution, it gives me a perfect level circle. I do not confine myself to one size of turn-tables or plates, but use such sizes as may be found necessary for the work, operating with the slotted slide k to accommodate the eccentric-lever to the turn-table.

What I claim as my invention, and desire to secure by Letters Patent, is—

The combination of the turn-table d, levelling-plate b, circle-plate e, the levers m, F, g, h, and o, rollers i and j, and slotted slide k, constructed and arranged as hereinbefore described, as a circle or elliptic bending-machine, for bending fifth-wheels and clip-circles of carriages, and sizing and lining clips.

WILLIAM MORGEY.
